FIG. 7

Gerard Johan Lught
By Fraser, Myers, Manley
Atlys.

rod 10 is on a cross head 11 which moves along a guide 12.

Beneath the engine cylinder 1 and the pump cylinder 8 a lever 16 is pivoted upon the point 15. Its end is connected to the motor piston 4 by a connecting rod 17, by which it is also driven. Further, the lever 16, in turn, drives the scavenging air pump through the medium of a connecting rod 18 applied to the cross head 11.

The movement of the pump piston 9 will be not only in time with the motor piston 4, but even in entire conformity with the movement of the motor piston, only with a smaller stroke. The coupling of these two pistons forms a pantograph system.

A piston rod 22 connected to the pump piston 9 passes through a stuffing box 20 in a cover 21 of the pump cylinder 8. A piston rod 22 forms the driving element for the auxiliary and controlling means.

The end of the rod 22 is provided with a cam body 23, against which a roller 24 is pressed. This roller 24 is mounted at the end of a lever-system 25, to which rocking levers 26 are connected, which levers control the valve rods 27 of the outlet valves 3. It will easily be seen that the shape of the cam 23 is such that at the end of the downward stroke of the motor piston 4 the outlet valves 3 open before the ports 2 open and that the outlet valves 3 remain open till the cylinder has been scavenged by air flowing through the ports 2 and the outlet valves 3. Adjustment can take place by varying the position of the cam 23 on the rod 22.

When it is required that the points of opening and closing of the valves or other elements are not symmetrical with respect to the dead centres, a phase-shifting mechanism must be applied in order to obtain the unsymmetrical movement required.

Furthermore the paper or registration drum 30 of the indicator mechanism is also driven from the rod 22, and a device for reversal and reduction of the movement is necessary. As such there is provided a shaft carrying cable drums 31 and 32 respectively of different diameters, on which the cables 33 and 34 respectively are wound in opposite direction. The former cable is attached to the indicator, the latter to the rod 22.

When "shifted" diagrams are required (showing a phase-difference of 90° with respect to the engine), another device for transformation of movement is provided for that purpose (e. g. a crank mechanism with cranks at 90°).

In the motor shown in the drawing, the starting valve device or its control device, the super-charging device (for introducing combustion air under pressure into the cylinder) and the fuel pump can be driven, controlled or regulated from the rod 22.

In Fig. 1a I have shown a fuel pump plunger a which is driven by a cam b on the piston rod 22 of the scavenging pump piston 9. The supply conduit for the fuel oil is indicated by reference character c and is connected to the fuel pump cylinder over a suction valve d. When the pump plunger a has been retracted the oil will circulate from the supply conduit c to the pump cylinder and back to the return conduit e in order to keep the oil flowing constantly. The fuel injector is indicated by the reference character f, and as a rule the injector f is not mounted on the corresponding motor cylinder 1 but on another cylinder of the same engine. It would be possible to have the injector f mounted on its own cylinder

but then a phase of shifting mechanism would be needed in order to obtain a longer injection period after the motor piston 4 has reached the outer dead center, which would complicate the design.

In Figs. 2, 3 and 4, a rod 101 forms the driving element. It may be, for example, the extended piston rod of a scavenging air pump driven by a balance from the cross head of an engine cylinder and consequently having a movement in the rhythm of the engine piston. The rod 101 carries a cross head 102 moving along the guide 103, and the cross head 102 carries a roller 104.

The outlet valve to be controlled is driven by a rod 105, which is fitted to a lever 106 pivoting about a fixed point 107. It will be understood that when the roller 104 moves up and down along a cam-surface on the lever 106, this lever 106 pivots about its fixed point 107 and thus acts upon the rod 105. Care has to be taken, that the movement of the lever 106, when the roller 104 moves downward, is different from the movement of the lever when the roller 104 moves upward. This can be effected by an arrangement in which different cams on the lever 106 are in contact with the roller 104 when it moves upward and when it moves downward.

For this purpose the lever 106 is provided with a cam unit 108 comprising a set of cams 109 (three cams) and a set of cams 110 (also three cams). The roller 104 consists of three coaxial discs of equal size co-operating with either the cams 109 or the cams 110. The position of the roller 104 is variable in axial direction in the cross head 102. When this roller 104 is in the position shown in Figs. 3 and 4, it co-operates with the cams 109, but when it shifts it co-operates with the cams 110. This shifting is effected with the aid of an arm rocking lever 111, which strikes an abutment 112 when the rod 101 moves downward. At the upper dead centre a shifting in the opposite direction has to be effected, and this can be done in the same manner by a rocking lever 113 co-operating with an abutment 114.

The position shown in Fig. 2 corresponds with the beginning of the opening of the outlet valve of the two-stroke engine. When the axis of the roller comes into the position indicated by the dotted line 115, the engine piston is at its lower dead centre and the movement reverses, the roller 104 now following the cam 110, so that the outlet valve is again closed when the axis of the roller is in the position indicated by the dotted line 116.

The roller 104 is divided into separate discs (three, in the drawing) in order that a small axial shift may suffice. In position 115 the discs are in contact with both the cams 109 and the cams 110, so that shifting can take place without shock. During the shifting at the lower dead centre an auxiliary roller (not shown) can be used in order to avoid contact between the roller 104 and the cams 109 and 110, so that shifting can take place without friction.

Of course the positions of the roller 104 and the cam 108 can be interchanged.

In the embodiment according to Fig. 5, as opposed to that of Figs. 2-4, the roller is immovably fitted in the cross head 102, but the cam is adjustable. For this purpose the lever 106 carries a single cam 120, which is adjustable with respect to the lever 106, viz. by means of two links 121 and 122, pivoted at the points 123 and 124 respectively of the lever 106. The other extremi-

ties of the links 121 and 122 are pivoted at the points 125 and 126 respectively of the cam.

At the downward stroke of the rod 101 the roller 104 presses the cam 120 against the fixed abutments 127 and 128 of the lever 106. The cam 120 is moreover maintained in that position by a tension spring 129, attached to the free end of the link 122. The position and the shape of the cam 120 are such that the rod 105 is acted upon at the correct moment. In the drawing the position corresponding with the initial opening of the outlet valve is shown. It is to be noted that the links 121 and 122 are not under stress, the whole force being taken up by the abutments 127 and 128.

After the roller 104 has passed the nose of the cam and is consequently applied to the fixed cam 119 of the lever 106, the rod 101 moves again upward, and the couple acting on the cam 120 under the influence of the pressure exerted on it by the roller 104 is inverted, as a result of which the cam is moved upward into the position shown in dotted lines.

Consequently the roller 104 runs upwards from the cam 119 along a cam surface of a shape or position which is different from that along which the roller 104 moved downward and in this way the closing of the valve is effected at the correct moment. When the roller 104 has passed the extremity of the cam, the latter is carried back to its original position shown in the drawing, under the influence of the spring 129. The dotted line 116 shows the position of the centre of the roller 104 at the moment that the outlet valve is closed. The dotted line 115 marks the lower dead centre.

In the embodiment of Fig. 6 the roller 104 forms a part of the lever 106, whereas the cross head 102 is provided with the cam. The roller 104 (which may be multiple) is mounted in a yoke 130 pivoted at a point 131. A spring 132 maintains the shaft 133 of the roller 104 in contact with a cam 134 on the lever 106.

When the cross head 102 moves downward, a cam 135 touches the roller 104, as a result of which the lever 106 is moved. The position illustrated corresponds with the beginning of this movement (opening of the outlet valve).

The lever 106 carries another roller 136 which is also controlled by the cam 135. When this cam 135 enters into contact with the roller 136, it loses contact with the roller 104, and when after having reached the lower dead centre it again moves upward, the roller 104 is pushed away and brought to the position 137 shown in dotted lines, so that the cam 135 is applied to the roller 136 only. This means that the lever 106 quickly swings back, the dotted line 116 marking the position at which the closing of the outlet valve takes place, and the position of the line 138 on the cross head 102, marking the beginning of the cam 135. When the cam 135 has again passed the roller 104 (in position 137) during its upward stroke, the spring 132 carries the roller 104 back to its original position.

Fig. 7 gives a solution to this problem which is of a different principle and which can be adopted specially when the stroke of the moving rod 101 is too small to get a practicable shape of cam within the path limited by the dotted line 140 (beginning of the opening of the outlet valve) and the dotted line 141 (lower dead centre). The outlet valve (not shown) is controlled by a connecting rod 142. A lever 144 is fitted to this rod 142 at the pivot 143. The point 143 is conducted

in a circular path by means of a link 145 pivoted at the fixed point 146, the circle of which coincides as much as possible with the evolute line described by the point 143 when the lever 144 rolls or is evolved on a curved fixed track 147. The other end of the lever 144 (pivot 148) is connected by means of a link 149 to a pivot 150 at the extremity of the connecting rod 101 moving up and down. At the upper dead centre 151 this link occupies the position 149' and the pivot 148 is at the position 148'. The curved evolving track 147 is pivoted at one end upon a fixed point 152, while it rests at the other end upon a two-arm lever 153 pivoted at the fixed point 154. At the lower dead centre the protruding pin 150 of the rod 101 presses against the extremity 155 of the lever 153, as a result of which the latter is put in the position shown in dotted lines and the guide 147 is pressed downward, pivoting upon the point 152, into the position shown in dotted lines against the abutment 156. Consequently the point 143 also drops, together with the pushing rod 142, so that in the upward stroke the closing of the valve comes earlier. The track 147 is then again completely discharged and a spring 157 causes the track 147 and the lever 153 to return to their original positions.

This construction may be varied in many ways. The track 147 can be fixed and the moving parts may be placed in the lever 144. The point 143 may also be guided in a right line instead of pivoting upon point 146. The abutment 156 may be provided with a buffer-mechanism in order to absorb the shock at the lower dead centre. The principle of this latter construction is that no cams and rollers are used, but instead of these a lever 144 rolls or evolves on a curved track 147, the position of the track 147 being different in the upward and downward movement of the connecting rod 101.

What I claim is:

1. A two-stroke internal combustion engine of the uni-directional flow type, comprising a power cylinder closed at one end, a reciprocating piston within the power cylinder, a crank shaft, a connecting rod and a crank operatively connecting the piston to the crank shaft, said cylinder being provided with outlet means in its closed end and with air inlet ports in its wall positioned to be uncovered by the piston when it nears its inner dead center, an air scavenger pump comprising a pump cylinder and a reciprocating pump piston within the pump cylinder, the pump cylinder being located adjacent the power cylinder, and the pump piston being provided with connecting rod mechanism operatively connected to the moving piston system of the power cylinder and also to the outlet means of the power cylinder, the outlet passages of the air pump being in communication with the air inlet ports in the wall of the power cylinder.

2. A two-stroke internal combustion engine of the uni-directional flow type, comprising a power cylinder closed at one end, a reciprocating piston within the power cylinder, a crank shaft, a connecting rod and a crank operatively connecting the piston to the crank shaft, said cylinder being provided with outlet means in its closed end and with air inlet ports in its wall positioned to be uncovered by the piston when it nears its inner dead center, an indicator device mounted on the power cylinder, a pump comprising a pump cylinder and a reciprocating pump piston moving within the pump cylinder, the pump cylinder being located adjacent the power cylinder, the

pump piston being provided with connecting rod mechanism operatively connected to the moving piston system of the power cylinder and also to the movable part of the indicator device which has to be driven in phase with the power system.

3. A two-stroke internal combustion engine of the uni-directional flow type, comprising a power cylinder closed at one end, a reciprocating piston within the power cylinder, a crank shaft, a connecting rod and a crank operatively connecting the piston to the crank shaft, said cylinder being provided with outlet means in its closed end and with air inlet ports in its wall positioned to be uncovered by the piston when it nears its inner dead center, a fuel pump of the reciprocating type having its outlet communicating with a fuel injector, a second pump comprising a pump cylinder and a reciprocating pump piston moving within the said pump cylinder, the pump cylinder being located adjacent the power cylinder, the pump piston being provided with connecting rod mechanism operatively connected to the moving piston system of the power cylinder and also to the reciprocating driving member of the fuel pump.

4. A two-stroke internal combustion engine of the uni-directional flow type, comprising a power cylinder closed at one end, a reciprocating piston within the power cylinder, a crank shaft, a connecting rod and a crank operatively connecting the piston to the crank shaft, said cylinder being provided with outlet means in its closed end and with air inlet ports in its wall positioned to be uncovered by the piston when it nears its inner dead center, a pump comprising a pump cylinder and a reciprocating pump piston moving within the pump cylinder, the pump cylinder being located adjacent the power cylinder, the pump piston being provided with connecting rod mechanism operatively connected to the moving piston system of the power cylinder and also to the outlet means of the power cylinder and a phase-shifting device mounted between the connecting rod mechanism of the pump and the outlet means of the power cylinder.

5. A two-stroke internal combustion engine according to claim 4 wherein the phase-shifting device comprises cooperating means to transmit the driving movement from the said pump to the said outlet means, one of said cooperating means having two different active parts which cooperate one at a time with the other of said means, said active parts being periodically shiftable for cooperation with the other of said means.

6. A two-stroke internal combustion engine according to claim 4 wherein said phase-shifting device comprises a roller and a cam unit consisting of two cams in staggered relation with respect to one another in a direction at right angles to the direction of the movement, said roller and cam unit being adjustable in a transverse direction with respect to one another in such a manner that either one cam or the other cooperates with the roller.

7. A two-stroke internal combustion engine according to claim 6, in which with respect to the roller and the cam unit only, the one located in

the driving element connected to the said pump is adjustable in a transverse direction by cooperation with abutment mechanisms near the ends of the stroke of the driving element.

8. A two-stroke internal combustion engine according to claim 4 wherein the phase-shifting device comprises a roller and a cam, one of which is movable in the plane of the relative movement from a working position to a different working position, or from a working position to an inactive position, a second cam or roller being provided in the latter case, with which the roller or cam respectively, can cooperate when the first mentioned cam or roller occupies its inactive position.

9. A two-stroke internal combustion engine according to claim 4 wherein the phase-shifting device comprises a roller cooperating with a cam, the cam being movably fitted in its own plane by means of links, the movement being limited by an abutment in one working position in such a manner that when the relative movement of the roller reverses, or after it has been discharged from the pressure of said roller, the cam turns away, thus forming or disengaging a different shape cam surface to cooperate with the roller.

10. A two-stroke internal combustion engine according to claim 4 wherein the phase-shifting device comprises a roller cooperating with a cam, the roller being movably fitted in its own plane and supported in its working position by an abutment, a second stationary roller being provided to cooperate with the cam when the first mentioned roller passes to its inactive position under the influence of the cam reversing its relative movement.

11. A two stroke internal combustion engine according to claim 2 wherein the pump is an air scavenger pump, the outlet passages of which are in communication with the air inlet ports in the wall of the power cylinder.

12. A two stroke internal combustion engine according to claim 3 wherein the second pump is an air scavenger pump, the outlet passages of which are in communication with the inlet ports in the wall of the power cylinder.

13. A two stroke internal combustion engine according to claim 4 wherein the pump is an air scavenger pump, the outlet passages of which are in communication with the air inlet ports in the wall of the power cylinder.
